F. M. SCHAEFFER, OF BLOOMING GROVE, KANSAS.

Letters Patent No. 83,324, dated October 20, 1868.

IMPROVEMENT IN SAWING-MACHINES.

The Schedule referred to in these Letters Patent and making part of the same.

To all whom it may concern:

Be it known that I, F. M. SCHAEFFER, of Blooming Grove, in the county of Linn, and State of Kansas, have invented a new and improved Sawing-Machine; and I do hereby declare that the following is a full, clear, and exact description thereof, which will enable others skilled in the art to make and use the same, reference being had to the accompanying drawings, forming part of this specification.

The object of this invention is to provide an improved machine for sawing logs into bolts or blocks, which may also be used for sawing trees for felling them.

It consists in an improved arrangement of guides for the saw; also, an improved means for adjusting the saw to work either in a horizontal or vertical plane; also, an improved means for holding a log while being sawed, to prevent the same from rolling; and, also, in an improved means for supporting the block which is being sawed off.

Referring to the drawings—

Figure 1 represents a plan view of my improved machine;

Figure 2 represents a side elevation of the saw-frame, and a cross-section of the log-frame; and

Figure 3 represents a detached portion, showing the means for changing the plane of the saw.

Similar letters of reference indicate corresponding parts.

A represents the saw-frame, and B the log-frame. C represents a driving-shaft, which may be operated by bevel-wheels, from the crank-shaft D, or by any other suitable means. The said shaft may be provided with one or more balance-wheels, which may also serve for communicating motion, by belts, to other mechanism. From the said wheels motion is communicated by connecting rods to the cross-head E, to which the saw-handle F is connected by a joint, which will admit it to oscillate, so as to work either in a vertical or horizontal plane, or in any plane at any angle to the same. The saw receives reciprocating motion from the said cross-head.

G represents guides, through which the saw-handle works, which are supported on the bolt H, projecting from the upper end of the lazy-tongs I, which are jointed, at the lower end, to the oscillating plate K, and provided at their central axis with a bolt, e', the head of which works in a groove in the plate K, whereby the said lazy-tongs are maintained in a vertical position, or in a position parallel with the said plate.

The plate K is jointed to the stand L, and provided with a bent screwed bolt, which is arranged to be adjusted in the arm l of the stand L, and secured at any position by the set-nuts l' and l'', whereby the saw may be adjusted to work in any desired plane.

The lazy-tongs serve to connect the said guides to the oscillating plate, and at the same time admit of the necessary rising and falling or swinging motion required for the saw to work through a log, and return again to the position for starting. M and M represent guides for the saw, which are also supported on the bolt H, and bear against each side of the saw, but which

may be turned upward on their axial support, and when the saw, in the act of sawing, works down into the log, they are prevented from moving down with it, and rest on the top of the log. They are borne downward by the springs m m, and when the log has been sawed off, and the blocks drop away from the saw, the said guides will be forced down, by the springs, to their proper position on each side of the saw. If the block on one side only falls away, the guide on that side will be forced down to its position, and the saw will be guided between that guide and the end of the log, while the saw continues to run in that position.

N represents a feeding-shaft, which is operated by a lever-pawl and ratchet, and is provided with the feeding-wheels o o, which may be arranged to be adjusted to and from each other on the shaft, and which are curved on their inner faces, and provided with ribs, as shown in fig. 1, which take into the surface of the log and hold with sufficient strength to feed it along, the other end resting on the carriage P. By reason of the curved inner faces of the said feeding-wheels, the log may be so securely held that it will not be rotated by the action of the saw.

Q represents a grooved oscillating support for the block which is being sawed off, which is provided with trunnions q q, and an arm, q', whereby it is supported on the frame, and connected, by a rod, to a hand or foot-lever, R, whereby the position of the said support may be adjusted to give the proper amount of support to the block. The said support is curved in a manner to cause the block to fall away from the saw after it has been sawed off, and a vigorous movement of the hand-lever R, in the right direction, will throw the block clear of contact with the support.

The frames B and A are connected together by suitable detachable connections, whereby they may be separated, and the log-frame removed, when the machine is to be used for felling trees, or for any other desired purpose.

I claim as new, and desire to secure by Letters Patent—

1. The arrangement of the guides M M and springs m m, with relation to the guides G and the saw, whereby said guides M move independently of each other, to press upon the log being sawed, as herein described, for the purpose specified.

2. The guides of a reciprocating saw, supported on an adjustable oscillating plate or support, K, substantially as and for the purpose described.

3. The combination, with the plate K and the saw-guides, of the lazy-tongs I, for the purpose of connecting the guides to the oscillating plate, and admitting of the rising and falling motion required by the saw in its passage through the log, substantially as and for the purpose described.

4. The swinging-block support Q, arranged as described, in combination with the log-bed, substantially as and for the purpose described.
